C. H. FELTEN.

DISPOSAL CAN.

APPLICATION FILED DEC. 28, 1920.

1,427,525.

Patented Aug. 29, 1922.

Inventor,
Charles H. Feltan
James C. O'Neal
By his Attorney

UNITED STATES PATENT OFFICE.

CHARLES H. FELTEN, OF WEST HOBOKEN, NEW JERSEY.

DISPOSAL CAN.

1,427,525.

Specification of Letters Patent. Patented Aug. 29, 1922.

Application filed December 28, 1920. Serial No. 433,690.

To all whom it may concern:

Be it known that I, CHARLES H. FELTEN, a citizen of the United States, and a resident of West Hoboken, in the county of 5 Hudson and State of New Jersey, have made a certain new and useful Improvement Relating to Disposal Cans, of which the following is a specification, reference being had to the accompanying drawings, which 10 form a part of the same.

An object of my invention is to provide a can of the garbage and ash can class which is susceptible to considerable abuse in such manner as to provide cushioning means to 15 take up the shock which would otherwise be sustained by the can causing damage thereto.

Another object of my invention is to provide a frame containing the cushioning means in which the container itself may be 20 securely fastened.

Referring now to the drawings.

Figure 1 is a central longitudinal cross-section of my can;

Figure 2 is a lateral cross-section of my 25 can taken along the line 2—2 of Figure 1;

Figure 3, is a fragmentary elevation view of my can showing the application of the protecting strips thereof; and

Figure 4 is an enlarged sectional detailed 30 view of the means for securing the strips in their frame and for securing the can in its frame.

Referring now in detail to the drawings in which similar letters refer to similar parts 35 throughout 1 represents the side wall of the can, 2 the bottom thereof, 3 the cover and 4 the handle.

The can is inserted in frame 5 which is 40 preferably made in channel form. This frame is provided with an annular collar 6 at each end thereof. Extending through the upper annular collar are lugs 7 which connect with and hold the can in position in the frame. At the bottom of the frame elements 5 I have provided flanges 8 which extend inwardly in the direction of the centre of the frame which flanges are adapted 45 to bear the weight of the can in the frame through the feet 9 of the can.

50 Spacing elements 10 are inserted between the collars 6 and the frame elements 5. The frame elements 5 are provided with studs 11 for the purpose of holding in place the spiral springs or elastic mediums 12. On each of 55 the frame elements 5 is mounted a cushioning strip 13 and in this cushioning strip 13 are provided bosses 14 which cooperate with

the studs 11 to hold the resilient element 12 in position.

I preferably slot the ends of the cushioning strips 13 which is shown by the slots 15 and said cushioning strips are attached to the frame through the rivets 16 inserted through spacing elements 10.

It will be observed that the resilient strips 65 13, the frame elements 5 and the upper and lower collars 6 are unified and form a frame work in which the can or container is adapted to be inserted and that the can is locked or fastened therein by means of the 70 lugs 7.

It is obvious that various modifications may be made in the construction of my device without departing from the spirit of my invention. I therefore do not wish to be 75 confined to the disclosure shown and illustrated but what I desire to cover by Letters Patent is set forth in the appended claims.

Claims:

1. In a disposal can, the combination with 80 a can, of a frame in which said can is adapted to be secured, said frame embodying supporting rings, frame elements secured at each end to one of said rings, resilient strips extending outwardly from said frame, supplemental resilient means cooperating 85 with said resilient strips, means in said frame to support a can, and means for locking said can in said frame.

2. In a disposal can, the combination with 90 a can, of a frame in which said can is adapted to be secured, said frame embodying supporting rings, frame elements secured at each end to one of said rings, resilient strips extending outwardly from said frame, means in said frame to support a can, and means for locking said can in said frame.

3. In a disposal can, the combination with 100 a can, of a frame in which said can is adapted to be secured, said frame embodying supporting rings, frame elements secured at each end to one of said rings, resilient strips extending outwardly from said frame and supplemental resilient means co-operating 105 with said resilient strips.

4. In a disposal can, the combination with 110 a can, of a frame in which said can is adapted to be secured, said frame embodying supporting rings, frame elements secured at each end to one of said rings and resilient strips extending outwardly from said frame.

CHARLES H. FELTEN.
